CLAIM

The ornamental design for an egg scrambling container as shown and described.

DESCRIPTION

FIG. 1 is a top front perspective view of an egg scrambling container showing my new design;

FIG. 2 is a front view of the egg scrambling container, a rear view being identical;

FIG. 3 is a right side view of the egg scrambling container, a left side view being identical;

FIG. 4 is a top view of the egg scrambling container;

FIG. 5 is a bottom view of the egg scrambling container;

FIG. 6 is an exploded front view of the egg scrambling container; and,

FIG. 7 is a bottom view of the egg scrambling container taken from line 7-7 in FIG. 6.

The broken lines in the drawings depict portions of the box scrambling container that form no part of the claimed design
